Attorney, Agent, or Firm—Cumpston & Shaw[57] CLAIM

The ornamental design for a combined eye wear and flexible strap temples, as shown and described.

DESCRIPTION

FIG. 1 is a perspective view of a combined eyewear and flexible strap temples showing my new design;
 FIG. 2 is a front elevational view thereof;
 FIG. 3 is a rear elevational view thereof;
 FIG. 4 is a right side elevational view thereof, the left side being a mirror image;
 FIG. 5 is a top plan view thereof;
 FIG. 6 is a bottom plan view thereof; and,
 FIG. 7 is perspective view thereof in an operable environment.
 The broken line showing of the pendants and the wearer head is for illustrative purposes only and forms no part of the claimed design.
